UNITED STATES PATENT OFFICE.

FRANK B. HOWELL, OF BUFFALO, NEW YORK, ASSIGNOR TO AMERICAN RADIATOR COMPANY, OF CHICAGO, ILLINOIS, A CORPORATION OF NEW JERSEY.

BOILER.

Application filed February 4, 1921. Serial No. 442,369.

To all whom it may concern:

Be it known that I, FRANK B. HOWELL, a citizen of the United States, residing at Buffalo, Erie County, in the State of New York, have invented certain new and useful Improvements in Boilers, of which the following is a full, clear, and exact specification.

My invention relates to improvements in heating apparatus, and the same has for its object more particularly to provide a boiler in which a more perfect combustion of the fuel and gases produced therefrom will be obtained.

Further, said invention has for its object to provide a boiler in which secondary air is admitted through the fuel receptacle and above the combustion chamber in order to preheat the same to a higher degree before 20 the same actually enters the combustion chamber to mix with the combustible gases entering the combustion chamber.

Further, said invention has for its object to provide a construction in which the secondary air is received in a chamber above the combustion chamber, preheated and thence caused to pass downward, and after impinging against a highly heated curved, perforated deflecting plate, finally to pass 30 through said plate in a large number of small jets and meet the highly heated combustible gases liberated or produced by the burning fuel and cause the same to be consumed without materially reducing the temperature thereof.

Further, said invention has for its object to provide a construction in which the combustible gases and the products of combustion, as they pass into the combustion 40 chamber, will be directed forcibly against a highly heated, deflecting plate forming the top of the combustion chamber and serving also as the bottom of the chamber or compartment in which the secondary air is heated to a high temperature before it 45 passes through suitable openings in said deflecting plate to mix with the on-coming combustible gases to render the same inflammable.

Further, said invention has for its object to provide a construction in which the deflecting and heating plates may be readily inserted into or removed from the furnace.

Further, said invention has for its ob-

ject to provide a construction in which the deflecting and heating plates are made in sections of unequal length so that boilers of different widths may be readily equipped.

Other objects will in part be obvious, and in part be pointed out hereinafter.

To the attainment of the aforesaid objects and ends, my invention consists in the novel details of construction, and in the combination, connection and arrangement of parts hereinafter more fully described and then pointed out in the claims.

In the accompanying drawings—

Figure 1 is a front elevation showing one form of boiler constructed according to, 70 and embodying my said invention;

Fig. 2 is a section taken on the line 2—2 of Fig. 3; and

Fig. 3 is a central, longitudinal section taken on the line 3—3 of Fig. 2. 75

In the accompanying drawings, I have shown my invention in connection with a sectional boiler of the cross-draft type in which a number of flue sections are arranged to the rear of the combustion chamber. It will, of course, be understood that the form of boiler herein shown and described has been selected merely to serve as a convenient means for illustrating the invention, and that the form or type of 85 boiler may vary.

In said drawings, the boiler shown is of the sectional type and which may be enlarged transversely as well as longitudinally. The boiler consists essentially of hollow 90 end members each comprising three sections, viz, a large forward section 10, and two smaller rear sections 11, 12, arranged one behind the other, and four intermediate transverse members which form a fuel receptacle 13^a, a combustion chamber 13^b, a secondary air chamber 13^c, and a series of flues 31 extending from the combustion chamber to the smoke outlet of the furnace. 95

The end and the intermediate sections of the boiler are enclosed by a suitable jacket or casing 14, provided at its top with one or more fuel openings 15, each having a hinged cover 15'. The jacket or casing 14 is provided in its front wall, adjacent to its top, with openings 16 having hinged doors 16' and deflecting plates 16^a, which are pref-

erably perforated and secured upon the inner sides thereof. Below said openings 16 may be provided one or more air supply openings 17, having a frame 17' provided with butterfly dampers 17^a. The dampers 17^a are connected at their inner lower edges by links 18 with an arm 19 secured upon a shaft 20 extending through the end section of the boiler and provided with an operating lever 21, which is connected to and actuated by a thermosensitive device 21^a, whereby said damper 17^a may be actuated in response to pressure or temperature changes within the boiler.

15 Below the frame 17' are arranged large fire openings 22 provided with hinged doors 22' to permit of access to the burning fuel, and below said fire openings 22 are ash pit openings 23 provided with hinged doors 23'.

At the rear of the boiler, adjacent to its base, is a smoke outlet 24 adapted for connection with a chimney or stack.

The front transverse member of the boiler 25 is composed of a series of hollow sections 10^a, which are of less height than the sections 10^b immediately to the rear thereof, and are connected together. The said sections 10^a, are provided at their upper and lower ends with nipples 25 whereby the same are secured together and to the end section members 10. The sections 10^a have a reduced lower portion 10^c provided upon its opposite sides with a plurality of downwardly and inwardly inclined fins 10^d forming air passages 10^e intermediate the same. At the lower ends, said sections 10^a are provided with downwardly and inwardly inclined toes 10^f.

40 The hollow sections 10^b extend from the base to the top of the boiler and are provided at their upper ends with inwardly-extending horizontal projections 26. The sections 10^b are provided at their upper and lower ends with nipples 26^a whereby the same are secured together and to the end section members 10. The lower portions of the sections 10^b are also reduced in width and provided upon their opposite sides with a plurality of upwardly and rearwardly-extending fins 27 forming passages 27' intermediate the same to carry off the products of combustion from the fuel receptacle 13^a, formed by the connected sections 10^a, 10^b and the end sections 10.

Near their upper ends, the opposing edges of the contacting flanges are partly cut away to form apertures 32, to provide communication between the upper portion of the fuel receptacle 13^a and the secondary air chamber 13^c.

60 To the rear of the sections 10^b are disposed two parallel transverse flue members composed of substantially rectangular sections 28, 29, provided at their upper for-

ward corners and at their lower, downwardly projecting portions 28', 29' with nipples 28^a, 28^b, 29^a, 29^b, whereby said sections are secured together and to their end section members 11, 12, respectively.

70 The rear edge of the section 28 is provided with laterally-extending peripheral ribs 28^c, and said sections 28 and 29 are provided upon their opposite sides with laterally-extending peripheral flanges 28^d, 29^d, and near their central portions with ribs 30, which extend rearwardly from the front edges of the downwardly projecting portions 28', 29', and thence upwardly about two-thirds the height of said sections, and form flues 31 extending from the combustion chamber 13^b to the smoke outlet 24.

80 The flue sections 29 are provided at the bottom of their forward edges with forwardly-extending projections 29^e which jointly form a ledge upon which is supported the lower edge of an arched, perforated, deflecting plate 33, whose upper edge extends forwardly and is supported upon lugs 34 extending rearwardly from the back of the sections 10^b.

85 The operation of the boiler is as follows:

The necessary primary air to support the combustion of the fuel is received through the air supply openings 17, and passes through the passages 10^e between the front sections 10^a. The products of combustion pass through the passages 27', between the rear sections 10^b, and into the combustion chamber 13^b where the same impinge 95 against the highly heated small jets of secondary air issuing from the apertures in said deflecting plate 33, and thereby cause the products of combustion to be completely consumed.

100 The secondary air issuing through the apertures in the plate 33 is received through the air supply openings 17, controlled by the butterfly dampers 17^a, when it passes upwardly through the openings 33^a provided at the upper ends of the front sections 10^a, through and around the deflecting plate 16^a, across the top of the fuel receptacle 13^a, into the apertures 32 in the upper portions 110 of the sections 10^b, and thence into the chamber 13^c, where the same become highly heated by their contact with the hot walls of said chamber, and with the arched deflecting plate 33. The preheated air is finally discharged in numerous small jets 115 or streams into the combustion chamber in a direction opposite to that in which the products of combustion enter the combustion chamber from the fuel receptacle.

120 The secondary air in passing through the top of the fuel receptacle 13^a and into the air chamber 13^c serves also to draw with it into said air chamber 13^c any gases or distillates produced by the fuel which would otherwise collect in 125 130

the top of said fuel receptacle and finally escape through the charging opening 15 into the building.

It will, of course, be understood that the 5 invention is not confined to the specific form of boiler which is herein shown and described, as the same has been selected merely as a means of illustrating the applicant's invention.

10 Having thus described my said invention, what I claim and desire to secure by Letters Patent is:—

1. A boiler comprising a fuel receptacle, flues, a vertical compartment arranged to 15 the rear of said fuel receptacle substantially coextensive in height therewith and provided near its top with air intake openings, and a partition arranged in said compartment dividing the same transversely to form 20 a combustion chamber and an air heating chamber above said combustion chamber; said partition having a plurality of discharge openings therein for the passage of heated air into said combustion chamber, substantially as specified.

2. A boiler comprising a vertical fuel receptacle, flue sections arranged to the rear of said fuel receptacle and spaced with respect thereto, a perforated plate having one 30 edge supported upon the rear of said fuel receptacle and its opposed edge supported upon the front of said flue sections and serving to divide the space intermediate said fuel receptacle and said flue sections into a 35 combustion chamber and a superposed air heating chamber, and means for admitting air to be heated to said air heating chamber, substantially as specified.

3. A boiler comprising a fuel receptacle, 40 flue sections arranged to the rear of said fuel receptacle and spaced with respect thereto, a perforated partition between said fuel receptacle and said flue sections dividing the space therebetween transversely to 45 form a combustion chamber and a superposed air heating chamber, and air intake openings between said air heating chamber and said fuel receptacle through which air is received into said air heating chamber 50 from said fuel receptacle, substantially as specified.

4. A boiler comprising a fuel receptacle, flues, a vertical compartment arranged between said fuel receptacle and said flues and 55 provided with air intake openings between the same and the upper portion of said fuel receptacle through which air is received into said compartment from said fuel receptacle, and a perforated member dividing said compartment transversely to form a combustion chamber and an air heating chamber above 60 said combustion chamber, substantially as specified.

5. A boiler comprising a fuel receptacle, 65 flues, a vertical compartment arranged be-

tween said fuel receptacle and said flues, and a perforated member dividing said compartment transversely to form a combustion chamber and an air heating chamber above 70 said combustion chamber communicating therewith, and air intake openings in said air heating chamber through which air is received into said air heating chamber, substantially as specified.

6. A cross-draft boiler comprising a fuel 75 receptacle, flues, a vertical compartment arranged to the rear of said fuel receptacle and substantially coextensive in height therewith and provided near its top with air 80 intake openings, and a curved partition arranged in said compartment dividing the same transversely to form a combustion chamber and an air heating chamber above said combustion chamber, said partition having a plurality of discharge openings 85 therein for the passage of heated air into said combustion chamber, substantially as specified.

7. A cross-draft boiler comprising a vertical fuel receptacle having draft openings 90 in its lower portion, flue sections, a vertical compartment arranged intermediate said fuel receptacle and said flue sections, a curved partition extending longitudinally 95 across said compartment and serving to divide the same to form a combustion chamber and a secondary air chamber above said combustion chamber, and means for supporting said curved partition; said secondary air chamber having air inlet openings 100 near its top, and said curved partition having a plurality of outlet openings therein for discharging preheated air into said combustion chamber, substantially as specified.

8. A cross-draft boiler comprising a vertical fuel receptacle having draft openings 105 in its lower portion, flue sections, a vertical compartment arranged intermediate said fuel receptacle and said flue sections, a curved partition extending longitudinally 110 across said compartment and serving to divide the same to form a combustion chamber and a secondary air chamber above said combustion chamber, means for supporting said curved partition; said secondary air chamber having air inlet openings near its 115 top, and said curved partition having a plurality of outlet openings therein for discharging preheated air into said combustion chamber, and means for controlling the supply of air to said air chamber, substantially as specified.

9. A cross-draft boiler comprising a vertical fuel receptacle having draft openings 120 in its lower portions, flue sections, a vertical compartment arranged intermediate said fuel receptacle and said flue sections, a curved apertured partition extending through said compartment and having its rear, lower edge supported adjacent to the 125

inlet portions of the flues in said flue sections and its forward, upper edge supported by the front wall of said compartment above the draft openings therein; said curved partition serving to divide said compartment into a combustion chamber and a secondary air chamber, and means in said air chamber adjacent to its top for admitting to said air chamber the air to be preheated, substantially as specified.

10. A boiler comprising a fuel receptacle, flues, a combustion chamber interposed between said fuel receptacle and said flues, and air heating chamber having inlet openings adjacent to its top communicating with said fuel receptacle and discharge openings in its base communicating with said combustion chamber, an air supply opening, a damper for said opening, means for controlling said damper, and a deflector arranged above said opening, substantially as specified.

11. A boiler comprising a fuel receptacle, flues, a combustion chamber interposed between said fuel receptacle and said flues, an air heating chamber above said combustion chamber having inlet openings adjacent to its top communicating with said fuel receptacle and discharge openings in its base communicating with said combustion chamber, an air supply opening, a damper for said opening, means for controlling said damper, and a perforated deflector arranged above said opening, substantially as specified.

12. A boiler comprising a fuel receptacle, flues, a combustion chamber interposed between said fuel receptacle and said flues, an air chamber above said combustion chamber having inlet openings adjacent to its top communicating with said fuel receptacle and discharge openings in its base communicating with said combustion chamber, an air supply opening in front of the boiler, a butterfly damper for controlling

said opening, a lever for operating said butterfly damper, and a perforated deflector arranged above said opening, substantially as specified.

13. A boiler comprising a fuel receptacle, a combustion chamber arranged to the rear thereof, and means for conducting secondary air above and to the rear of said fuel receptacle, heating said secondary air and discharging the same into said combustion chamber in opposition to the direction of the products of combustion entering said combustion chamber, substantially as specified.

14. A boiler comprising a fuel receptacle, a combustion chamber to the rear thereof, a smoke outlet and flues extending from said combustion chamber to said smoke outlet, and a secondary air receptacle arranged to the rear of said fuel receptacle and above said combustion chamber and communicating therewith, a perforated partition separating said secondary air receptacle from said combustion chamber, and means for supplying air to said secondary air receptacle, substantially as specified.

15. A boiler comprising a vertical fuel receptacle, flue sections arranged to the rear of said fuel receptacle and spaced with respect thereto, a smoke outlet communicating with said flues, a curved perforated plate having its upper edge supported upon the rear of said fuel receptacle and its lower edge supported upon the front of said flue sections and serving to divide the space intermediate said fuel receptacle and flue sections into a combustion chamber and a superposed air heating chamber, and means for admitting air to be heated to said air heating chamber, substantially as specified.

Signed at the city of Buffalo, Erie County, in the State of New York, this 13th day of December, one thousand nine hundred and twenty.

FRANK B. HOWELL.
